UNITED STATES PATENT OFFICE.

CHRISTIAN ABELE, NEW YORK, N. Y.

MILL FOR GRINDING GRAIN.

SPECIFICATION forming part of Letters Patent No. 247,870, dated October 4, 1881.

Application filed December 14, 1880. (No model.)

To all whom it may concern:

Be it known that I, CHRISTIAN ABELE, of the city, county, and State of New York, have invented new and useful Improvements 5 in Mills for Grinding Grain, of which the following is a specification.

This invention pertains to certain improvements in mills for grinding grain and other articles, and which belong to a class known as 10 "portable mills," or those in which the grinding apparatus is mounted in a frame—one for each mill—so as to be in a compact form, and which, as an entire or completely organized apparatus, may be moved from place to place 15 as desired.

The invention consists in certain combinations and arrangements of devices, which devices will be fully explained in the specification, and will appear as forming the subject- 20 matter of the claims.

In the drawings, Figure 1 represents a sectional elevation of the mill. Fig. 2 is a detailed view of the device for supporting the shoe. Fig. 3 is a plan of the mill as seen from 25 above the hopper.

At A is represented the main frame for supporting the entire apparatus, and at B is a supplemental frame, which is hinged to the upper side of the main frame by strong hinges, (shown 30 at C.)

The runner or revolving stone is shown at D, and the stationary stone is represented at E, and is mounted in a circumferential metal hoop or band, (shown at F,) and which is 35 formed with lugs cast upon its outer and upper corners, three of which are shown in the drawings at F', and said lugs are of sufficient strength to support the stone in a vertical position upon the supplemental frame, which is 40 hinged to the main frame; and through said lugs are arranged set-screws, as shown at G, provided with regulating-nuts, so that the stationary stone may be raised or lowered at pleasure, and to any degree desired, either for the 45 purpose of adjusting the stone in the proper position or for the purpose of compensating for any wear that may take place on its surface; but in addition to said regulating-nuts and supporting-screws there are also binding- 50 screws, as at H, projecting inwardly from opposite sides of said supplemental frame, the ends of which project in against the perimeter

of the stone, so that when it is once adjusted in position by the vertical screws the said set-screws will be set up firmly against it for the 55 purpose of holding it in a fixed position. By such a construction of the parts, or the means of supporting the stationary stone, it is evident that it may be adjusted and fastened in its supporting-frame in any desired and fixed 60 position, and so held that when any dressing of the stone is required it is only necessary to remove the hopper from above the stationary stone, and then with an ordinary pulley-block lift the stone and its frame up and turn it back 65 upon the hinges which connect said supplemental frame with the main frame, so that the stone may be turned face upward, and at the same time expose the face of the runner or lower stone; and after the dressing of the 70 stone is completed the said supplemental frame with its suspended stone may be again turned back into position, and, the adjustment not having been disturbed, will be ready at once to proceed with the operation of grinding, as no 75 further adjustment will be required than simply to close the frame.

The lower stone is mounted in the usual manner on a spindle, as at K, the lower end of which is supported in a step, as at L, said 80 step being supported in a step box or casting which is mounted upon a cross-beam, as at M, that extends across from one side of the frame to the other.

The step-box is shown at N, and is held by 85 keys extending through notches in the said cross-beam M, so that it may be moved to and fro in any direction required for adjusting the step or lower end of the spindle; but the lower end of the spindle itself rests upon plates of 90 metal held in recesses in a supplemental box, as at O, the lower end of which rests upon a lever, as at P, which extends across from a beam forming a portion of the main frame underneath said step-box, and is supported at its 95 other end by means of a regulating rod and screw, as at R and R'. The upper end of said regulating-rod is supported in a bracket, as at R², fastened upon the upper face of the supplemental frame, and said bracket is notched, so that the rod may be raised up and placed 100 into said notched end, and thereby readily moved in and out of position; but when in position the hub of the hand-wheel R³ will keep

said rod from dropping out of the bracket, as the hub works in a circular recess in the bracket R², and which is represented in Fig. 1 as in working position. By such an arrangement it is evident that the runner or lower stone, which is supported on the spindle, the step of which rests on the lever P, and the stationary stone, which rests upon the hinged or supplemental frame, may be drawn or forced 10 toward each other by means of said regulating-rod, and with as great a degree of power as can be exerted on the hand or regulating wheel.

The step-box of the spindle is provided with plates at the bottom, as shown at O, for the 15 spindle to rest upon, and instead of the side of the spindle bearing against the box itself there is a sleeve or bushing of steel, as at S, inserted inside of said box, which works sufficiently loose to serve as a bearing for the 20 spindle, so that if the friction is greatest between it and the spindle, said sleeve will turn in the box, or vice versa, as the case may be.

The hopper is represented at T, and underneath it is suspended a shoe, as at T', one end 25 being supported by a pivot or finger, as at T², and the other end supported by a cord, as at T³, one end of which is wound around a regulating-shaft, and upon said regulating-shaft is a ratchet-wheel and pawl, as at T⁴ and T⁵; but 30 around the same regulating-shaft there is another cord, as at W, which extends around a pivot or small pulley, as at W', and which is connected to a spring, as at W², one end of which is attached, so that as the shoe is raised 35 or lowered the tension on said spring will be varied accordingly, and consequently when the shoe is lowered to a very considerable position, and the cord at T³ would thereby be of considerable length, and the shoe would have a tendency 40 to swing over from the knocker-staff, the tension on the spring W² would be increased, as its cord would be wound up at the same time that the cord supporting the shoe would be unwound, and in this way the pressure on the 45 knocker-staff would be kept substantially the same in whatever position the shoe may be adjusted.

Above the bush that surrounds the upper end of the spindle there is a collar-plate, as 50 at X, which has a boss or a flange upon its upper face extending entirely around the spindle, and over said flange the hub of the sweep-staff, as at Y, fits in such a manner as to pre-

vent any grain or meal from falling down around the spindle into the bush, as the concave portion of the said hub at Y fits down snugly over the flanged portion of the collar above the bush, and thus effectually covers the parts around the spindle.

In a mill so constructed it is evident that if 60 the parts be so combined that when the stones are separated they may be again brought together without disturbing their previous adjustments, there will be great advantages 65 gained in the grinding of articles when the stones must be separated frequently and the faces cleaned and sharpened, as in the grinding of herbs or other materials beside grain.

I therefore claim—

1. In a portable mill, the combination of the 70 fixed or stationary stone E, provided with the circumferential hoop or band F, having lugs F' and set-screws G, supplemental frame B, for supporting the fixed stone, hinged at one side to the main frame, and provided at the 75 opposite side with an open slotted bracket, R², regulating-screw R R', and hand-wheel R³, for holding the stone in place, as hereinbefore shown and described.

2. In combination with the shoe of a grind-ing-mill, the regulating-shaft W⁴, suspended above the lower end of shoe, cord T³, connecting shoe with regulating-shaft, and spring W², attached at one end to shoe and at the other through medium of cord W to regulating-shaft, whereby, by turning the regulating-shaft, the shoe through cord T³ is raised, and through cord W is drawn against the knocker-shaft, and thus the proper position of the shoe 85 is maintained.

3. In a portable mill, the combination, with the frame B, hinged at one side to the main frame, of the open or slotted bracket R², secured to the hinged frame, and provided with a slotted or open front portion and a circular groove 95 within its top, hand-wheel R³, and regulating-rod R R', for the purposes hereinbefore set forth.

In witness whereof I have hereunto subscribed my name in the presence of two sub- 100 scribing witnesses.

CHRISTIAN ABELE.
